UNITED STATES PATENT OFFICE

2,140,056

FIGURE TOY

Philip Joseph Piro, New Orleans, La., assignor of
one-half to Alcide J. Austin, New Orleans, La.

Application September 21, 1937, Serial No. 164,977

2 Claims. (Cl. 46—119)

This invention relates to figure toys, and more particularly, to a toy simulating the movements of a bootblack during the operation of shining a shoe.

- 5 An object of this invention is to provide a toy which will provide amusement and which is so constructed that the operation of reciprocating a shoe shining cloth over a shoe is simulated by a figure mounted on a base structure.
- 10 Another object of this invention is to provide a toy of this kind with improved means whereby the shoe shining cloth may be reciprocated back and forth over a shoe, the operating means for the cloth being provided in a figure disposed in a 15 kneeling position on a base.

With the foregoing and other objects in view, the invention will be more fully described herein-after, and will be more particularly pointed out in the claims appended thereto.

20 In the drawing, wherein like symbols refer to like or corresponding parts throughout the several views:

Figure 1 is a perspective view of a figure toy constructed to an embodiment of this invention.

25 Figure 2 is an enlarged fragmentary sectional view taken on the line 2—2 of Figure 1.

Figure 3 is an enlarged sectional view taken on the line 3—3 of Figure 1.

Figure 4 is a fragmentary sectional view taken 30 on the line 4—4 of Figure 2.

Referring to the drawing, the numeral 10 designates generally, a base structure which is provided at a suitable point thereupon with a block 11 having a shoe rest 13 disposed on the upper side thereof. A figure 12 has one leg 14 thereof resting on and preferably secured to the base 10 adjacent one end of the base, and the other leg 15 of the figure 12 has the foot 16 thereof resting on the shoe rest 13.

40 A second figure, generally designated as 17, is disposed in a kneeling position on the base 10 in a position substantially facing the figure 12. The figure 17 represents a bootblack or boy, and the figure 17 is provided with pivoted arms 18 and 19 extending on opposite sides of the upstanding block or support 11. The hands 20 and 21 of the arms 18 and 19 respectively, have secured thereto a flexible shoe shining member 22 which extends over the shoe 16 of the figure 12 in substantially a V-shape, and the opposite ends of the flexible member 22 are secured as by rivets 23 and 24 to the hands 20 and 21 respectively.

45 The body 25 of the figure 17 is preferably hollow and a power means for rocking the arms 50 18 and 19 is disposed within the body 25. This

power means comprises a frame 26 which is fixedly mounted in the body 25, and a drive shaft 27 is rotatably carried by the frame 26 and is provided with a key 28 which is disposed outwardly of the body 25.

5 A spring 29 is operatively engaged with the drive shaft 27, and a gear 30 is secured to the drive shaft 27 and meshes with a pinion 31 mounted on a shaft 32 journaled in the frame 26. A second gear 33 is mounted on the shaft 32 and 10 meshes with a driven gear 34 carried by a crank shaft 35 which is rotatably mounted in the frame 26. The shaft 35 is provided with a crank 36 at one end and a second crank 37 at the opposite end.

15 A rock shaft 38 is rockably supported by the upper portion of the body 25 and has one end 39 thereof, fixedly secured to the arm 18 so that rocking of the shaft 38 effects rocking movement of the arm 18. A second rock shaft 40 is rockably 20 carried by the body 25 and the outer end 41 of the rock shaft 40 is fixed to the arm 19. The rock shaft 38 is provided with an elongated loop 42 within which the crank 36 operates, and the rock shaft 40 is provided with a similar loop 43 25 within which the bell crank 37 operates. The bell cranks 36 and 37 are preferably diametrically disposed so that upon rotation of the shaft 35, the arms 18 and 19 will be rocked in directions so as to effect a reciprocatory or back and forth movement of the shoe shine cloth or flexible member 22.

30 In the use and operation of this toy, the flexible member 22 is loosely disposed over the shoe 16 and when the spring 29 is wound up, the gear train comprising the gears 30, 31, 33, and 34, will rotate the shaft 35, and rotation of the shaft 35 will effect rocking movement of the shafts 38 and 40 through the cranks 36 and 37 which are 35 loosely disposed in the loops 42 and 43 respectively. Vertical rocking movement of the arms 18 and 19 is thus effected with the arm 18 moving in a direction opposite from the arm 19 so that the cloth or strip 22 will simulate the wiping or polishing operation of the bootblack on the 40 shoe 16.

45 It is, of course, understood that various changes and modifications may be made in the details of construction and design of the above specifically described embodiment of this invention without departing from the spirit thereof, such changes and modifications being restricted only by the scope of the following claims.

50 I claim:

55 1. A toy comprising a base, a block secured to

said base, a figure secured in upstanding position on said base and having a foot resting on said block, a second figure mounted on said base in substantially a kneeling position, said second figure including a pair of vertically rockable arms disposed one on each said side of said block, a flexible foot wiping member carried by said arms and engaging over said foot, a rock shaft carried by said second figure for each of said arms, an elongated loop carried by each rock shaft, said loops being formed as integral continuations of the shafts, and motor operated crank arms within the second figure and each loosely engaging within one of said loops whereby to effect rocking movement thereof to thereby vertically rock said arms.

2. In a device of the character described, a figure having a pair of arms, a motor mechanism within the figure and including a driven rotary

shaft having a crank at each end, a pair of rock shafts disposed in side by side parallel relation within and across the said figure from one side to the other, each of said rock shafts extending at one end to the exterior of the figure and secured to an arm to effect oscillation of the same vertically, an elongated rectangular frame formed from and consisting of an integral lateral extension of each shaft adjacent one end thereof, said motor being between the frames and each frame having a crank disposed therein, said cranks being oppositely directed and adapted upon rotation of the driven shaft to move in said frames and swing the latter, one of said rock shafts passing through the frame of the other rock shaft, and means joined to the arms for actuation thereby upon oscillation of the arms.

PHILIP JOSEPH PIRO.

CERTIFICATE OF CORRECTION.

Patent No. 2,140,056.

December 13, 1938.

PHILIP JOSEPH PIRO.

It is hereby certified that the name of the assignee in the above numbered patent was erroneously described and specified as "ALCIDE J. AUSTIN" whereas said name should have been described and specified as ALCIDE J. AUTIN, as shown by the record of assignments in this office; and that the said Letters Patent should be read with this correction therein that the same may conform to the record of the case in the Patent Office.

Signed and sealed this 31st day of January, A. D. 1939.

Henry Van Arsdale

(Seal)

Acting Commissioner of Patents.
